UNITED STATES PATENT OFFICE.

WALTER JUEDE, OF CHICAGO, ILLINOIS, ASSIGNOR TO THEO. A. KOCHS COMPANY, OF CHICAGO, ILLINOIS, A CORPORATION OF ILLINOIS.

DESIGN FOR A BARBER'S POLE.

Application filed December 3, 1928. Serial No. 29,101. Term of patent 7 years.

To all whom it may concern:

Be it known that I, WALTER JUEDE, a citizen of the United States, residing at Chicago, in the county of Cook, and State of Illinois, have invented a new, original, and ornamental Design for a Barber's Pole, of which the following is a specification, reference being had to the accompanying drawing, forming part hereof.

The figure is a front elevation of a barber's pole showing my new design.

I claim:

The ornamental design for a barber's pole, as shown.

WALTER JUEDE.
